HERBERT E. MARKS, OF SEWICKLEY, PENNSYLVANIA.

ROOF AND FLOOR CONSTRUCTION.

Application filed May 25, 1923. Serial No. 641,390.

The invention relates to fireproof flat arch constructions and in the drawings is illustrated as designed particularly for a roof construction, but manifestly it can be adapted for floors and other similar uses.

The object of the invention is to provide a flat arch construction having a minimum weight with maximum strength, and one which is cheap to construct and erect due in part to the reduction in the amount of weight of material used and to be handled, and in part to dispensing with the usual false work or centering during erection.

In the accompanying drawings Fig. 1 is a vertical section through a roof constructed according to the invention, the section being taken transversely of the hollow blocks or tiles employed; Fig. 2 is a vertical section taken at right angles to that of Fig. 1, on the line 2—2; Fig. 1; Fig. 3 is a perspective view showing the manner of assembling the blocks or tiles; Figs. 4, 5, 7 and 8 are transverse vertical sections showing modified forms of blocks or tiles and modified means for supporting them; Fig. 6 is a plan view showing the form of device shown in Fig. 5 for supporting the blocks or tiles during erection; and Fig. 9 is a detailed sectional view showing a modification of the water shedding covering the concrete beam.

In the drawings 1 indicates the main supporting members for the flat arch, and which in the case of a roof will be the purlins or similar beams. The flat arch is formed of a series of blocks or tiles 2, preferably hollow as illustrated so as to reduce weight and secure heat insulation, and which will be of the minimum vertical depth for the desired strength. These blocks or tiles are provided at their lower side edges with laterally projecting flanges 4, are designed to be placed in parallel rows with the flanges 4 of adjacent rows substantially abutting, and the space between adjacent rows is then filled with concrete, gypsum or other cementitious material which entirely fills said space, bonds the adjacent rows of blocks or tiles together and forms a concrete beam 5 extending at right angles to the main supporting beams 1. The blocks or tiles may or may not be provided on their side faces with grooves or recesses of various forms and depths into which the concrete 5 can key. The drawings show

simple longitudinal grooves 3, except in Fig. 7 which shows the blocks provided with substantially plain faces, which can be used in case the cementitious material for filling the space is of a dense closely adhering character, such as in the so-called "Gunite" process. When plain side faces are used it is preferred to make them somewhat inclined, as shown in Fig. 7. To prevent the cementitious material from leaking out when applying it, a suitable cover 4^a, such as a strip of felt, paper or the like, may be used to cover the space between the edges of the flanges 4. To strengthen the beams 5 a reinforcing member or members 5^a is located in the space between adjacent rows of blocks or tiles, fairly well down toward the bottom of said space and becomes embedded in the concrete and forms the tension member of the beam 5. This tension member may be horizontal, or it may be blocked up where it passes over the main beams or purlins 1 and allowed to curve downwardly between the main beams or purlins, as shown in Fig. 2.

In order to provide sufficient strength in the beams 5 and still keep the vertical depth of the hollow blocks or tiles 2 to a minimum, said beams are formed of greater depth than the body of the blocks or tiles. To permit this, the blocks or tiles are provided along their upper side edges with ribs or flanges 6 which extend a material distance above their top faces, to such height to give the desired depth to the beams 5 molded between them. The concrete forming the beams 5 will be filled up substantially or nearly to the top of the ribs or flanges 6, and will preferably be provided with a cover of suitable waterproofing material, such as a layer 7 of asphalt or the like, which will be built up slightly higher than the tops of the ribs or flanges 6 and preferably will be slightly crowned so as to shed water from the tops or beams. The tops of the ribs or flanges 6 may be correspondingly curved, or sloped, as shown. In lieu of the asphaltum cover 7 the beams may be rendered waterproof by placing over them tile or like caps 8, as shown in Fig. 9.

The spaces between the abutting ends of the individual blocks or tiles will be filled with a suitable waterproofing material, such as asphalt, shown at 9. In order to provide

of the blocks at their upper surfaces are cut away to provide channels 10, which preferably extend upwardly along the side faces of the ribs or flanges 6 and also across their tops, as shown in Fig 3.

The tops of the tiles will preferably be glazed so as to dispense with waterproofing, and will be left uncovered, but if desired a layer of asphaltum or other suitable waterproofing material may be applied to their faces, but otherwise the top faces of the tiles will remain exposed. Consequently the top faces of the blocks or tiles form a water shed for carrying off the water. Their bottom faces may also be glazed. The upper faces of these tiles may be curved as shown in Figs. 1 and 3, being of maximum depth at their longitudinal centers and of minimum depth adjacent to the ribs or flanges 6, thus forming in effect two gutters on each row of tiles or blocks for carrying away the water; or the tops of said blocks may be curved from their side flanges 6 downwardly from their longitudinal centers, as shown in Fig. 4, or they may be flat, as shown in Figs. 5, 7 and 8.

The flat arch construction described has a minimum weight with maximum strength due to the fact that the greater portion of the area thereof is formed by the bodies of the hollow tiles or blocks of minimum depth, only the side flanges and the intervening concrete beams being of full height. This reduces the amount of material entering into the construction, and also the amount and weight of material to be handled in shipping and erection. This is one element tending to reduction in cost.

The tiles and blocks are preferably so constructed that they can be placed in position without the use of the usual false work or centering. To this end the said tiles or blocks are provided with longitudinal slots for receiving supporting members extending longitudinally of the blocks or tiles and of a sufficient length to joint together and simultaneously support a row of tiles or blocks of a length at least sufficient to bridge the space between adjacent main supporting beams 1. As shown in Figs. 1 to 4 these longitudinal slots are in the form of openings 12 in the upstanding ribs or flanges 6, said openings preferably being rectangular in shape and of a size to receive bars 13 of sufficient strength to support the row of blocks and hold them in alignment. The bars 13 will be threaded through the openings of a series of said blocks of a length to bridge at least two adjacent beam members 1 and the entire series can then be handled as a unit and placed in position. After a sufficient number of such units have been put in place, the longitudinal spaces between adjacent rows of such blocks will be filled with concrete or grouting to the desired depth and the whole

then left to set. After the concrete has set sufficiently to support the structure, the bars 13 are removed endwise, and can be used for assembling and supporting other blocks which are then put in place and the operation repeated until the entire roof deck or other structure is completed.

If desired the supporting bars can be threaded through the side openings 14 of the bodies of the hollow tiles or blocks, with the same effect as above described.

In Figs. 5 and 6 the longitudinal slots for the supporting members are shown in the form of grooves 15 formed in the inner faces of the upstanding ribs or flanges 6, and are adapted to be engaged by the bottom flanges of channel shaped members 16, which are connected by any suitable means which will hold them with their flanges in engagement with the grooves 15, such for instance as the toggle members 17 pivotally connected to the channel members at 18 and to each other at 19. In using these connected channel members a number of blocks will be placed end to end in a series sufficient to bridge the space between adjacent beams 1; the channel members 16 will then be lowered down onto the same between the lateral flanges 6, the toggle members 17 will be straightened to spread the channel members and bring their bottom flanges into the grooves 15, and hold them in that position; whereupon the entire series of blocks can be handled as a unit, placed in position and will be held in position by these channel members while the concrete is poured and until it sets, after which the toggle members will be flexed and the frame removed and used in connection with other blocks.

Various other forms of longitudinal slots and of supporting bars may be used. Fig. 7 shows longitudinal slots 21 formed in projections 22 on the upper face of the tiles or blocks and which slots open up through the tops of said projections. The supporting bars 23 in this instance are of T-shape, and will be assembled with and removed from the blocks or tiles by endwise movement, exactly as in the case of the bars 13 of Figs. 3 and 4. Fig. 8 shows slots in the form of a pair of longitudinal grooves 24 on opposite sides of projections 25 on the upper faces of the blocks or tiles, thus making substantially T-shaped heads; and the supporting bars 26 are of inverted channel form with inwardly projecting flanges 27 engaging the grooves 24. These also are assembled with and removed from the blocks or tiles by endwise movement, exactly as in the case of the bars 13 of Figs. 3 and 4.

The flat arch construction described is of minimum weight with maximum strength. The strength is secured by providing sufficient depth to the concrete beams 5. The main portion of the flat arch being formed

by the bodies of hollow tiles or blocks, is of minimum depth and therefore of light weight. The top surfaces of the bodies of these blocks or tiles is left substantially uncovered. As stated the tiles preferably will be glazed in which case they will be themselves be water proof and need no further waterproof covering. This is a further element tending to reduction of cost. If desired however said top surfaces may be left unglazed and the entire surface then covered with a thin coating of waterproofing substance, without however materially adding to the weight of the finished structure.

Also the method of assembling and supporting the hollow blocks during erection and during pouring and setting of the concrete which forms the beams, is such that no false work or centering of any kind need be employed. This is a further element tending to greatly reduce the cost of the finished structure. The supporting bars 13, 23 or 26, or the equivalent members 16 and 17, can be used over and over again, as is obvious.

I claim:—

1. A fireproof flat arch construction comprising tiles or blocks arranged in rows and spaced apart, said tiles or blocks being provided along their upper side edges with ribs or flanges projecting above their top surfaces, the lower edges of the body portion of the blocks being provided with longitudinal side recesses and laterally projecting flanges, in combination with reinforced cementitious beams in the spaces between said rows of blocks and extending up in the space between the side ribs or flanges of said blocks and keyed into the longitudinal side recesses in said blocks.

2. A fireproof arch construction for roofs and the like comprising tiles or blocks arranged in rows and spaced apart, said tiles and blocks being provided at their upper side edges with upwardly extending ribs or flanges and at their bottoms with laterally extending flanges and provided in their side faces with longitudinally extending grooves or recesses, in combination with cementitious beams filling the spaces between said blocks and keyed into the longitudinal side recesses thereof and extending up into the spaces between the side ribs or flanges on said blocks, and waterproof material covering the joints between the abutting ends of said blocks.

3. A fireproof flat arch construction for roofs and the like comprising hollow tiles or blocks arranged in rows and spaced apart, said blocks being provided at their upper side edges with upstanding ribs or flanges, the top surfaces of said blocks being lowest adjacent to the side flanges and higher between the same, a waterproof filling at the abutting ends of said blocks, and cementitious beams in the spaces between said rows of blocks and extending up between the side ribs or flanges of said blocks, and a water shedding covering over the tops of said beams.

4. A fireproof arch construction for roofs and the like comprising a plurality of tiles disposed in end to end relation, each of said tiles being provided with a slot for temporarily receiving a removable supporting member adapted to operatively engage a plurality of said tiles during the course of erection, the receiving slots of the several tiles being disposed in longitudinal alignment with each other whereby to permit free withdrawal of said temporary supporting member after erection of the roof.

5. A fireproof arch construction for roofs and the like comprising a plurality of tiles disposed in parallel rows with similar tiles, said tiles having a plurality of longitudinal upstanding ribs provided with slots for temporarily receiving a removable supporting member engaging a plurality of said tiles during the course of erection, the receiving slots of the several tiles being disposed in longitudinal alignment with each other whereby to permit free withdrawal of said temporary supporting member after erection of the roof.

6. A fireproof arch construction for roofs and the like comprising a plurality of hollow tiles or blocks provided at their upper side edges with ribs projecting above their top surfaces, said ribs having longitudinal slots for removably receiving a temporary supporting member during the course of erection, said blocks having their lower side edges equipped with laterally projecting flanges, the receiving slots of the several tiles being disposed in longitudinal alignment with each other whereby to permit free withdrawal of said temporary supporting member after erection of the roof.

In testimony whereof, I sign my name.

HERBERT E. MARKS.
